MULLING APPARATUS

Walter F. Piper, Oak Park, Ill., assignor to The
Beardsley & Piper Company, Chicago, Ill., a
corporation of Illinois

Application February 13, 1939, Serial No. 256,096

2 Claims. (Cl. 83—45)

The present invention relates generally to apparatus for mulling granular material. More particularly the invention relates to that type of mulling apparatus which is especially designed for use in a foundry or like establishment in connection with the mulling or conditioning of molding sand and as the main or essential parts thereof comprises (1) a frame structure; (2) a sand retaining receptacle which embodies an annular side wall and is rotatably supported; (3) a plurality of rotary mulling elements which are disposed in the receptacle adjacent to the side wall and are adapted during rotation or drive of the receptacle to squeeze the sand against the inner face of the side wall; and (4) an electric motor which is mounted on the frame structure and is connected through the medium of a speed reducing unit to rotate the receptacle.

One object of the invention is to provide a mulling apparatus of this type in which the receptacle is mounted for rotation about a horizontal axis and has one end thereof open for the entry and discharge of batches of sand and its other end closed, and the motor and speed reducing unit which constitute the driving medium for the receptacle are mounted on the supporting structure adjacent to, and outwardly of, the end wall and as a result they are readily accessible for repair, replacement or inspection purposes, and in addition, are not likely to have any of the sand to be mulled or the mulled sand come in contact therewith.

Another object of the invention is to provide a sand mulling apparatus of the type and character under consideration in which the mulling elements are two in number and of wheel type and are mounted and urged outwards in a novel manner in order to effect efficient mulling of the sand between them and the side wall of the receptacle.

A further object of the invention is to provide a mulling apparatus of the last mentioned type and character in which the wheel type mulling elements are positioned above the axis of the receptacle with the result that they tend partially to support the receptacle and thus reduce the load on the main receptacle supporting means.

A still further object of the invention is to provide a sand mulling apparatus which is simpler and less costly than, and is generally an improvement upon, previously designed sand mulling apparatus including that forming the subject matter of an application for United States Letters Patent filed by me September 19, 1936, Serial No. 101,555.

Other objects of the invention and the various advantages and characteristics of the present sand mulling apparatus will be apparent from a

consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a vertical longitudinal sectional view of a sand mulling apparatus embodying the invention;

Figure 2 is a vertical transverse sectional view taken on the line 2—2 of Figure 1 and illustrating in detail the manner in which the wheel type mulling elements are supported within the receptacle; and

Figure 3 is a vertical transverse sectional view taken on the line 3—3 of Figure 1 and showing in its operative position the scraper which constitutes a part of the means for discharging the milled sand from the receptacle.

The apparatus which is shown in the drawings constitute the preferred embodiment of the invention. It is designed primarily for use in a foundry or like establishment in connection with the mulling or conditioning of molding sand and comprises a frame structure 4, a sand holding or retaining receptacle 5, a pair of mulling elements 6, and an electric motor 7.

The frame structure 4 is designed or adapted to rest on the floor of the foundry in which the apparatus is used and serves as the main supporting medium for the operating parts of the apparatus. It is rectangular and comprises a pair of horizontally extending laterally spaced parallel side beams 8, and a transversely extending horizontally positioned cross beam 9. The

cross beam 9 extends between and is welded or otherwise fixedly secured to the central portions of the side beams and serves to cross-connect and hold in laterally spaced relation the side beams. In addition to the side beams 8 and the cross beam 9, the frame structure 4 comprises a pair of bed plates 10 and 11, and an upstanding framework 12. The bed plate 10 is located at one end of the frame structure and serves as a pedestal or base for the electric motor 7. It is positioned outwardly of the bed plate 11 and is suitably connected to and supported above the subjacent ends of the side beams 8. The bed plate 11 serves to support a speed reducing unit 13 and is suitably connected to the side beams

8 of the frame structure.

The unit 13 together with the electric motor 7 constitutes the driving means for the receptacle 5 and comprises a casing 14, a drive shaft 15, and a horizontally extending driven shaft 16. The drive shaft 15 is aligned with the armature shaft

of the electric motor and is connected to such shaft by a coupling 17. The driven shaft 16 is journaled in a bearing 18 in the casing 14 and is connected by suitable gearing in the casing for low speed drive from the shaft 15. The outer end of the driven shaft 16 projects an appreciable distance beyond the bearing 18 of the casing and is disposed over the central portion of the frame structure 4. The framework 12 is located over the ends of the side beams 8 which are remote from the electric motor 7 and the speed reducing unit 13. It consists of uprights and cross-pieces which are suitably secured together so that the framework as a whole is of rigid design.

The receptacle 5 is disposed between the framework 12 and the speed reducing unit 13 and is adapted to be charged with a batch of sand to be mulled by way of a chute 19. It is generally cylindrical in contour or design and consists of an annular side wall 20 and a circular end wall 21. The side wall 20 is of uniform diameter from one end thereof to the other and is adapted to have the sand to be mulled squeezed against the inner face thereof by the mulling elements 6. The end wall 21 is joined to and formed integrally with one end of the side wall 20 and has in the central portion thereof a hub 22. The latter is mounted on the projecting end of the driven shaft 16 of the speed reducing unit 13 and is keyed to such shaft so that when the unit is driven by the electric motor 7 the receptacle 5 is in turn driven or rotated about a central horizontal axis. An inwardly extending ring-shaped flange 23 is formed integrally with the other end of the side wall 20 of the receptacle and defines a circular opening 24 for the entry and discharge of the sand. The chute 19 is carried by the framework 12 of the supporting structure 4, as shown in Figure 1, and is adapted to deliver a batch of sand to be mulled into the receptacle via the opening 24. The lower discharge end of the chute 19 extends through the opening 24 and terminates above the lower portion of the receptacle side wall. When the receptacle is driven by the motor 7 through the medium of the speed reducing unit 13, the sand adheres to the side wall of the receptacle as a result of the fact that it is subjected to the action of centrifugal force. The motor and speed reducing unit are of such design that they drive the receptacle at a sufficient speed to maintain the desired adherence of the sand to the receptacle side wall. If the receptacle is four feet in diameter it is rotated at forty or more revolutions per minute.

The two mulling elements 6 are in the form of wheels, and, as shown in Figures 2 and 3, are disposed one opposite the other in the upper portion of the receptacle 5. They are mounted rotatably on stub shafts 25 and operate during drive or rotation of the receptacle to effect mulling of the sand by squeezing it against the inner face of the side wall 20. The shafts 25 are positioned in parallel relation and project through the circular opening 24 in the flange 23. The outer ends of the shafts are fixed within cylindrical sockets 26 in the central portions of a pair of vertically extending arms 27. The lower ends of the arms are pivotally connected by pins 27a to a pair of brackets 28 on the top flanges of the cross beam 9 of the frame structure 4 so that the arms together with the wheel-type mulling elements are free to swing inwards and outwards with respect to the receptacle side wall. A compression spring 29 extends between the upper

ends of the arms 27 and serves to urge the arms apart so that the mulling elements in turn are urged outwards against the receptacle side wall for mulling purposes. A rod 30 extends through holes 31 in the upper ends of the arms 27 and prevents lateral displacement of the spring 29. Nuts 32 are mounted on the outer ends of the rod 30 and limit outward swinging movement of the arms 27. When the apparatus is in operation the sand in the receptacle is effectively mulled as a result of the squeezing action which takes place when it encounters the outwardly urged wheel type mulling elements 6. In order to agitate and aerate the sand and prevent the latter from becoming caked against the side wall, two scrapers 33 are provided. These scrapers are shaped conformably to, and are almost in contact with, the inner face of the receptacle side wall 20 and are carried by the framework 12 of the supporting structure. They extend through the opening 24 in the ring-shaped flange 23 and are positioned in front of the wheel type mulling elements 6, as shown in Figure 3. When the apparatus is in operation, the sand after being squeezed against the side wall of the receptacle by one of the mulling elements encounters the scraper in front of the other element and is scraped from the receptacle side wall and directed inwardly in an aerated manner into contact with the other element. After being subjected to the action of the other mulling element, the sand encounters the other scraper and is scraped by the latter from the receptacle side wall and directed inwardly in an aerated manner towards the other mulling element. As a result of successive squeezing and aeration of the sand by the joint action of the mulling elements and scrapers, the sand is effectively mulled in the receptacle. The inner faces of the scrapers are so angled or positioned that they direct the scraped sand inwardly at an abrupt angle into contact with the mulling elements 6.

In addition to the supporting structure 4, the receptacle 5, and the other hereinbefore described parts, the apparatus comprises means for discharging the sand from the receptacle after mulling thereof. Such means comprises a discharge chute 34 and a scraper type deflector 35. The discharge chute 34 is positioned alongside of the discharge end of the chute 19, as shown in Figure 2, and extends downwardly from the upper portion of the interior of the receptacle through the opening 24 in the flange 23. The upper end of the chute 24 is infundibular or funnel-shaped and is positioned between the wheel type mulling elements 6. The lower end of the chute projects into the space between the side beams 8 of the frame structure 4 and is adapted to direct the mulled sand into a hopper or onto a conveyor. The deflector 35 is positioned over the upper end of the chute 34 and is pivotally connected by a pin 36 to a bracket 37 on the framework 12 so that it may be swung back and forth between an operative position wherein the leading edge thereof is disposed adjacent to the inner face of the receptacle side wall and an inoperative position wherein it is beneath the top portion of the side wall and for the most part within the upper end of the discharge chute 34 as shown by dotted lines in Figure 1. When the deflector is in its operative position, the leading edge thereof serves to scrape the sand from the side wall of the receptacle as the latter revolves and the trailing or lower portion of the deflector oper-

ates to direct the scraped sand downwards into the upper end of the chute 34. When the deflector is in its inoperative position it is out of contact with the sand and has no scraping effect on the latter. The deflector 35 is controlled by means of a lever 38 and it is of such length that when it is in its operative position it extends across substantially the entire distance between the side wall 21 and the flange 23 and as a result operates to effect discharge of the entire mass or batch of sand within the receptacle during one revolution of the latter. The lever 38 is pivotally connected to a bracket 39 on the framework 12 of the supporting structure 4 and is connected to the scraper type deflector 35 of the discharge means by means of an arm 40 and a link 41. The arm 40 is fixed to and depends from the pin 36, as shown in Figure 1, and the link 41 extends between and is pivotally connected at its ends to the central portion of the lever 38 and the lower end of the arm 40. When the lever 38 is swung in one direction the deflector 35 is swung into its operative position and when the lever 38 is swung in the opposite direction the deflector is caused to swing or move downwards into its inoperative position within the upper end of the discharge chute 34. A retractable dog 42 and a gear segment 43 serve releasably to lock the lever 38 in its various positions.

When it is desired to operate the apparatus, the motor 7 is first started so as to effect rotation or drive of the cylindrical receptacle 5. Thereafter the batch of sand to be mulled is introduced into the receptacle by delivering it into the upper end of the chute 19. Such chute, as hereinbefore described, operates to deliver or direct the sand into the receptacle. As the sand is delivered into the receptacle it comes in contact and revolves with the side wall 20. As the sand passes the wheel type mulling elements 6 it is squeezed against the side wall by the elements and the desired mulling is effected. If bonding material is mixed with the sand it becomes uniformly distributed over the various grains of sand as the result of the squeezing and mulling action of the elements 6. During drive of the receptacle the scrapers 33 in front of the mulling elements operate as hereinbefore described to scrape the squeezed sand from the receptacle side wall and to throw or direct it inwards in an aerated manner into contact with the mulling element 6. When it is desired to discharge the sand from the receptacle after mulling of the sand to the proper or desired extent, the lever 38 is swung so as to swing or shift upwardly the scraper type deflector 35 into its operative position. As soon as the deflector reaches such position it operates to scrape the sand from the side wall of the receptacle and to direct it into the upper end of the discharge chute 34.

The herein described mulling apparatus consists of but a small number of parts and hence may be manufactured at a low and reasonable cost. It is extremely efficient and effective as far as the mulling of molding sand is concerned and is characterized by the fact that the electric motor 7 and the speed reducing unit 13 are positioned in horizontal alignment with the closed end of the receptacle as distinguished from beneath the receptacle and hence are readily accessible for repair, replacement or inspection purposes and are not likely to have any of the

sand to be mulled or the mulled sand come in contact therewith. An advantage of having the receptacle mounted on a horizontal axis and the speed reducing unit 13 positioned adjacent to and outwardly of the closed end of the receptacle is that the gearing of the unit need not be of the bevel gear variety. The apparatus is further characterized by the fact that the discharge of the mulled sand is substantially instantaneous in that it takes place during a single revolution of the receptacle. Because the wheel type mulling elements 6 are positioned above the center or axis of the receptacle and are urged outwards by the compression spring 29 the load on the bearing 18 of the casing of the speed reducing unit 13 is materially lessened.

Whereas the apparatus has been described as being primarily or particularly designed for use in a foundry in connection with the mulling of molding sand, it is to be understood that it may be used for the conditioning or mulling of other granular material. It is also to be understood that the invention is not to be restricted to the details set forth, since these may be modified within the scope of the appended claims, without departing from the spirit and scope of the invention.

Having thus described the invention, what I claim as new and desire to secure by Letters Patent is:

1. A mulling apparatus comprising in combination a frame structure, a receptacle for the material to be mulled supported by a shaft and bearing to rotate on a fixed substantially horizontal axis and embodying an annular side wall concentrically arranged with respect to said axis and having one end thereof open and its other end closed and connected to said shaft, means for rotating the receptacle, a pair of oppositely disposed mulling elements positioned adjacent to the inner face of the side wall and for the most part above the axis of rotation of the receptacle and having frame-structure-carried supporting means therefor whereby they are permitted to move toward and away from said side wall, and pressure means for urging the elements outwards against said side wall so as to cause them to squeeze the material against the side wall for mulling purposes during rotation of the receptacle and also assist in supporting the receptacle.

2. A mulling apparatus comprising in combination a frame structure, a receptacle for the material to be mulled supported by a shaft and bearing to rotate on a fixed substantially horizontal axis and embodying an annular side wall concentrically arranged with respect to said axis and having one end thereof open, means for rotating the receptacle, a pair of oppositely disposed rotary mulling elements positioned adjacent to the inner face of the side wall and above the receptacle axis of rotation and having frame-structure-carried supporting means therefor whereby they are permitted to move toward and away from said side wall, and spring means associated with and applied to the supporting means for urging the elements outwards towards the receptacle side wall so as to cause them to squeeze the material against the side wall for mulling purposes during rotation of the receptacle and also assist in supporting said receptacle.
